SIGNALING SYSTEM

Manfred W. Muehler, Nutley, N. J., assignor to
American District Telegraph Company, Jersey
City, N. J., a corporation of New Jersey

Original application August 3, 1940, Serial No.
350,623. Divided and this application Decem-
ber 16, 1944, Serial No. 568,519

6 Claims. (Cl. 177—360)

This invention relates generally to signaling systems and more particularly to such systems used for transmission and reception of fire alarm, waterflow alarm, watchman's tour and burglar signals.

This application is a division of my copending application Serial No. 350,623, filed August 3, 1940, for "Signaling system," Patent No. 2,365,719, issued December 26, 1944.

The system is particularly adapted for automatically receiving signals of the types outlined above, making a record of the signals and retransmitting certain of the signals, such as fire and police alarm signals to the fire or police headquarters. Prior systems have required manual retransmission and also manual attention during trouble conditions. This system provides automatic line switching and clearing apparatus for controlling and enabling the system to receive signals even though the various types of line fault conditions occur. Furthermore, the equipment functions without adjustment with any amount of leakage on the line circuit provided it is only on one side of a transmitter in operation. Prior McCulloh systems, both manual and automatic, have required relay adjustments, particularly during leakage conditions, these adjustments necessarily distorting the signals and frequently changing to cause loss of signals.

This system also incorporates a different type of signal which comprises break impulses and simultaneous make and ground impulses, thereby eliminating the prior normal impulse which is necessary in McCulloh systems of the old types. Elimination of the normal impulses permits more of the line time or the digit time to be devoted to the other forms of impulses whereby all impulses may be of longer duration. The transmitters used in the system are equipped with commutator type code wheels instead of the usual pen spring type, thereby eliminating the necessity of any adjustment in the field and also maintaining a constant impulse ratio.

The primary object of the invention is to provide a new and improved central station signal receiving and retransmitting apparatus.

Another object of the invention is to provide a central station signal receiving apparatus particularly adapted for automatic operation.

Still another object of this invention is to provide a signaling system which is particularly adapted for obtaining instantaneous McCulloh operation.

Further objects and advantages of this invention will be apparent to those skilled in the art

after consideration of the following specification taken in connection with the accompanying drawings, wherein:

Fig. 1 is a circuit diagram illustrating a signal transmission circuit together with the signal receiving relays;

Fig. 2 is a circuit diagram of the timing and routing relays together with a register; and

Fig. 3 illustrates the preferred form of transmitter code wheel which is used in the transmitters on the line circuit.

The invention will now be described generally in order to convey a general impression of the circuit layout. The system is provided with 15 transmission line 1 in the form of a loop including any desired number of transmitters 2. Each transmitter is equipped with a commutator type code wheel having successive conducting segments therein, as illustrated in Fig. 3 of the drawings. There are two such code wheels in 20 each transmitter, each wheel being connected to one side of the transmitter loop. The two code wheels are electrically connected together on the same shaft and in addition a ground wheel is also 25 mounted on the same shaft for the purpose of grounding the transmitter wheels during their operation. The ground wheel is provided with an undercut portion which normally or in the "rest" position removes ground from the code 30 wheels. Referring to Fig. 3, code wheel 60 normally rests in the position shown and rotates in the direction indicated by the arrow. The segment 62 in each of the code wheels, together with the contact spring 61, maintain the line circuit 35 in a normally closed condition whereby a supervisory circuit is provided. When the code wheel 60 is rotated, the line is broken by the long space following segment 62, this space being followed by a prefix digit consisting of three make and 40 ground impulses, as illustrated in Fig. 3 by way of example only. Each type of alarm is assigned a particular code prefix digit whereby the signal may be identified at the central station. The prefix digit is followed by a space somewhat 45 shorter than the initial break signal space whereby the central station apparatus may identify the first digit of the number code which follows the prefix digit. As the wheel 60 continues its rotation, the number digits are transmitted until 50 the long break impulse at the end of the signal terminates the operation of the central station apparatus and restores the line circuit to normal when spring 61 contacts the segment 62.

Signals are received at the central office 55 through the line and ground relays L and G, re-

spectively. The line and ground relays in turn control a repeating relay R. However, if trouble conditions occur in the line circuit 1, the B relay operates in the event of breaks in the line and makes appropriate switching operations for continuing relays L and G in operation to control the relay R. If the trouble conditions are in the nature of grounds either in the lines or in the boxes, the Q relay switches the windings of the relay R to render them operative under the control of the relays L and G.

In Fig. 2 of the drawings, the relay T is a digit timing relay which ascertains the end of each digit and the end of each prefix, while the relay TT is a main timing relay for timing the duration of one round of signals and restoring the apparatus to normal for receiving a succeeding round of signals.

The relays X, Y and Z perform a routing function and respond to various prefix digits for routing special signals, such as fire and police alarm signals to the fire and police headquarters transmitting relays F. H. Q. and P. H. Q.

Relays U and V are auxiliary switching relays for controlling the timing of relay TT and performing other special switching functions which will be described in greater detail in the following:

LINE SUPERVISING CIRCUIT

The normally supervised line circuit may be traced from plus battery through relay winding G1, out through the line circuit 1. After passing through the transmitters 2 of the line circuit, the circuit is completed through back contacts 4 of relay Q, and 3 of relay B, through winding L1, through back contacts 8 of relay B and 1 of relay Q, winding G2 and contact 10 of relay B to ground. The line relay L is normally energized and relay G unoperated owing to the fact that the windings G1 and G2 are differentially wound.

NORMAL CONDITIONS

OPERATION OF A TRANSMITTER

Transmitters used with this system are equipped with commutator type code wheels instead of the usual type employing pen springs. In the normal rest position of the transmitter the line circuits are closed between the two line brushes through the normal segments and hub on the commutator. In the normal position, the ground is removed from the commutator by means of an undercut portion on the hub segment. After the normal segment, it will be noted that there is a break equivalent to approximately three tooth spaces, which is to allow sufficient time for switching operations, to be described at a later point. After this break impulse the code may be cut as required.

NORMAL LINE CIRCUIT OPERATION

First break impulse

Assuming a transmitter to be in operation, at the time of the first break impulse when the code wheel springs leave the normal segment, relay L is deenergized due to the opening in the line circuit through its winding L1. With release of relay L, relay B is energized through circuits traced from ground through back contacts 2 or relay L, 12 of relay B, 8 of relay Q, and winding BR to plus battery. Relay B locks in through the circuit traced through back contact 8 of relay Q, make contact 9 of relay B to ground, later

also through conductor 20 and multiple contacts 5 of relay TT and 5 of relay T and make contact 11 of relay B. Relay R is energized through the circuit traced from ground through back contact 2 of relay L, through winding R2, back contacts 15 of relay Q and 1 of relay G to plus.

Timing relays

Relay TT is energized at this time through the circuit traced from plus, through make contacts 5 of relay B, 10 of relay R, and 10 of relay T, winding TT to ground. Relay TT locks in through the circuit traced from plus, through make contact 8 of relay TT, winding TT and to ground. Shortly after the operation of relay R, relay T drops out due to the shunt across its windings by make contact 5 of relay R and line.

At this time it will be mentioned that relays T and TT are slow to release relays, the delayed release being obtained by means of a shunt across each of their respective windings. This delay, in the case of relay T, is sufficient to prevent its falling out on the break between ground impulses of a digit of the code. The delay on relay TT is sufficient to prevent dropping out between digits of a code. With the release of relay T, relay X is energized through the circuit traced from plus through make contact 7 of relay R, line 24, back contacts 4 of relay Y, 7 of relay Z, 9 of relay T, and winding XI to minus.

Line circuit switching

At the time relay B operates, the return side of the line 1 is switched by the B relay contacts through make contact 4 of relay B, winding L1, make contact 7 of relay B to minus auxiliary battery. The application of the auxiliary battery to the line circuit may produce a capacitive charging effect on the line circuit of sufficient intensity to cause a momentary reenergization of relay L, momentarily deenergizing relay R. This, however, has no effect on the operation of the other relays, except that it may slightly delay the release of the relay T and the energization of X just previously traced. With this switching operation the G2 coil is removed from the circuit; therefore from this point on the equipment is not affected by any differential action of the G relay.

First ground impulse

On the first ground impulse from the transmitter the G relay is energized through its winding G1 to plus battery and relay L is energized through its winding L1 to the minus auxiliary battery. Relay R is released, due to the open circuit through its winding R2 at back contacts of relays L and G. Relay X remains energized despite the opening of make contact 7 of relay R from plus through back contact 8 of relay R (this is a make-before-break type contact), line 25, make contacts 6 of relay X, line 26, and 16 of relay B, back contact 8 of relay U and winding X2 to ground. At this time relay Q is energized through the circuit traced from plus through make contact 2 of relay G, winding Q1, back contacts 12 of relay Q, 9 of relay R, make contacts 13 of relay B and 1 of relay L to ground. Relay Q locks in through the circuit traced from plus battery through winding Q2, and make contacts 10 of relay Q, line 28, and 3 of relay TT to ground. With release of relay R, relay T is energized through the circuit traced from plus through make contact 2 of relay TT and winding T to ground.

Second break impulse

On the subsequent break impulse, relays L and G release due to the opening in the line circuit. This causes reenergization of relay R except that this time both windings R1 and R2 are energized through circuits traced as follows: From plus battery through back contact 1 of relay G, winding R1 and make contact 2 of relay Q to ground. Also from plus battery through make contact 14 of relay Q, winding R2, through back contact 2 of relay L to ground. With the operation of relay R, relay U is energized through the circuit traced from plus battery through make contact 1 of relay TT, line 29, make contact 4 of relay R, line 30, back contact 1 of relay Z, make contact 1 of relay X, winding of relay U and make contact 4 of relay T to ground. Relay U locks in through the circuit traced from plus through make contacts 1 of relay TT, 1 of relay U, winding of relay U and contact 4 of relay T to ground.

Code impulses to register

On the next (second) ground impulse, relays L, G, operate and R releases as before. In addition the register receives an impulse at this time due to the fact that relay U has been energized. This circuit may be traced from plus through make contact 1 of relay TT, line 29, back contact 3 of relay R, line 31, make contact 2 of relay U, through the register to ground.

On succeeding break and ground impulses relays L, G and R operate as previously covered to record the remainder of the impulses of the code in a similar manner to that just described. The register circuit, however, may be completed through contacts 1 of relay Y and 2 of relay Z in multiple with contact 2 of relay U for the various digits of the code. The operation of the relays X, Y and Z will be explained at later portion of the description in connection with the automatic selection of headquarters retransmission repeater circuits.

Clearing operations

At the end of the code transmission a long break (minimum of four tooth spaces) takes place before the code springs complete the line circuit at the normal segment. During this break relays L and G release as previously described causing energization of relay R. Relay T releases after a short delay due to the shunt of contact 5 of relay R across its winding T. Relay TT also releases after a delay due to the shunt across its winding by the back contact 11 of relay T through line 33, make contact 12 of relay R and line 34, and 2 of relay V (the operation of relay V will be explained later). The position of the slider of the variable resistor 15 may be adjusted for the required drop out time desired on relay TT.

With the release of relay TT the locking circuit for relay Q is broken due to the opening at contact 3 of relay T, 3 of relay TT and 3 of relay Z. (Relays Y and Z release due to openings in the various holding circuits, to be explained in detail later.)

Second round of signals

Let us assume that the transmitter is a multi-round type, in which case as the transmitter is in operation, the code springs in passing over the normal segment will cause the following operations: Relays L and G will energize, in turn causing release of relay R, and operation of relay Q,

as previously described, at the start of the signal. Relay TT will reenergize through the circuit traced from plus through back contact 13 of relay R, line 33, back contact 11 of relay T, winding TT, resistor 15 to ground. Relay T will energize through the circuit traced from plus through make contact 2 of relay TT the resistor and winding T to ground. This relay locks in through its make contact 1 of relay T, as before. On the break impulse after this normal, relays L and G release as before, causing operation of relay R. Relay U is energized through the circuit traced from plus through make contact 1 of relay TT, line 29, make contact 4 of relay R, line 30, back contact 1 of relay Z, make contact 1 of relay X, winding of relay U and contact 4 of relay T to ground at the same time a shunt is applied across the winding of relay T, by contact 5 of relay R, causing it to drop out after a slight delay. With the release of relay T, relay U drops out due to the open condition in its circuit at make contact 4 of relay T.

Clearing operations

The remainder of the round or, in the case of transmitters which have more than two rounds, the signals are transmitted as previously covered up to this point. On the long break following the last round of the signals, relays L, G, R, T, TT, Y, Z and Q function as covered at the end of the first round. When the transmitter reaches normal, at which position it comes to a stop, relays L and G energize as before, causing release of relay R. With the energization of relays L and G, relay Q energizes. Relays TT and T energize through circuits previously traced. Shortly after the operation of relay T, relay TT drops out due to the shunt across its winding TT by means of make contact 10 of relay T, and back contact 11 of relay R. Relay B reaches the to openings in its holding circuits at various contacts 5 of relay TT, 5 of relay T and 8 of relay Q. With the release of B, the line circuit is switched so that both ends are connected to plus battery thereby causing release of relays L and G. This circuit may be traced as follows: From plus battery, through winding G1, through the line circuit 1 returning through make contact 6 of relay Q, back contact 8 of relay B, relay winding L1, back contact 3 of relay B, make contact 5 of relay Q, and plus battery. Relay R is re-energized through circuits previously traced through its winding R1 and R2, causing energization of relay TT with the subsequent release of relay T which drops out after a short delay. This in turn causes the release of relay TT.

Relay Q next releases due to the open condition in its holding circuits through contacts 3 of relay T, 3 of relay TT and 3 of relay Z. This switching operation returns the line circuit to its normal condition and the L relay picks up through its winding L1. The operation of relay L is aided at this time by current through its local winding L2, this circuit being traced as follows: From plus battery, through back contacts 9 of relay TT, 13 of relay T, line 35, 16 of relay Q, 15 of relay B, and winding L2 to ground. It will be noted that upon release of relay Q and prior to the operation of relay L, the operating circuit of relay B is closed for a short instant. However, relay B is provided with a retarding winding BF, short-circuited by contact 6 of relay B. This arrangement makes relay B slow operating and prevents its operation on the short impulse it receives.

With the operation of relay L, the circuit through the R relay winding R2 is interrupted causing the release of the R relay, which in turn causes the energization of relay TT through circuits previously traced. Back contact 9 of relay TT opens and deenergizes winding L2. Relay T also reenergizes with the closing of contact 2 of relay TT. This in turn causes the release of relay TT due to the shunt circuit across its winding by make contacts 10 of relay T and back contact 11 of relay R.

Release of relay R also breaks the circuit for relay X at make contact 7 of relay R, the other locking circuit through back contact 8 of relay R being open at contacts 16 of relay B and 17 of relay Q. This returns all relays to their normal position and prepares the circuit for receipt of a signal from any other transmitter on the line circuit. Should a second transmitter on the line circuit start operation during these clearing out operations its operation will not be affected. The difference in this case being that some of the switching operations which take place at the start may be omitted depending on the condition of the relays at the time the second transmitter starts.

OPERATION WITH LEAKAGE ON THE LINE CIRCUIT

A leakage condition may exist on a circuit that is not sufficient to affect the L or G relays until after retransmission starts. If this be the case, after the first operation of L or G when the line circuit has been switched for operation, either or both of these relays may be affected, as will be discussed below.

CASE 1

Leakage on "L" relay side of transmitter

The first case of leakage to be considered will be that of leakage on the line of sufficient value to hold in the L relay preventing it from following subsequent break impulses of the transmitter. On the break impulse following the normal segment when a transmitter is in operation relay L releases and relays B, R, and TT operate as covered in the previous case. However, we assume in this case that after the switching operation has taken place, the leakage will cause operation of relay L and hold it in on subsequent signals. Directly following the operation of relay B, therefore, relay L will reenergize. This is different from the preceding description for normal operation as relay L remained deenergized in that case during the total break impulse. Operation of relay L causes release of relay R due to the open condition in its operating circuit through winding R2 at back contact L. Relay X now operates, this time through the circuit traced from plus through back contacts 8 of relay R, line 25, 9 of relay Z and 8 of relay Y, line 26, through make contact 16 of relay B, line 27, back contact 6 of relay U and winding X2 to ground. On the first ground impulse from the transmitters, relays G and Q operate through the same circuits as traced for normal operation. On the subsequent break impulse of the transmitter to cause operation of relay R, relay X stays locked in through its winding X1 through make contacts 7 of relay R, line 24, and 6 of relay X and winding X1. Relay U operates as described for normal operation.

It may be pointed out that if the leakage is not so strong as to make L pick up upon applica-

tion of the auxiliary battery to the line circuit, the operation during the first break impulse is as described above for normal operation; otherwise the operation is for both cases as follows:

5 On all subsequent coding impulses of the transmitter the relays and register operate as covered under "Normal operation" except as previously mentioned the L relay does not release at any time. During the long break between rounds of signals and when the code springs are passing over the normal segment, relays G, R, T, TT, Y, Z function the same as covered under "Normal operation."

After the last digit of the code of any round 15 of a multi-round transmitter, the relays also function as covered under "Normal operation" up to the point where the B relay is deenergized. At this point, four conditions may exist as listed below:

- 20 1. The L relay may remain energized through the leakage and G deenergized.
2. The G relay may remain energized and L deenergized.
3. Both relays L and G may remain energized.
4. Both L and G may release as the leakage resistance may be of such a high value that the current will be insufficient to affect either relay. In this case all clearing operations will be as covered under "Normal operation."

Condition 1.—If the L relay remains energized after the line circuit has been switched by the release of the B relay, the remainder of the clearing operations takes place as follows: With the release of relay G, relay R is energized through the winding R1 and make contact 2 of relay Q to ground. Relay TT energizes with the closure of make contact 10 of relay R, through make contacts 13 of relay Q, 10 of relay R, 10 of relay T and winding of relay TT, through the resistor to ground. Relay T is shunted by make contact 5 of relay R, and drops out after a short delay, in turn causing the release of relay TT, as previously covered.

In comparing the chart for this condition with 45 that of the normal conditions, it will be noted that no further operation of the relays takes place, as covered under "Normal operation." In this case, the Q relay does not release as it is held in through the circuit traced from plus battery, through winding Q2, make contact 9 of relay Q, and make contact 1 of relay L to ground.

Condition 2.—This case differs from the preceding one in that the G relay energizes and L remains deenergized, due to the leakage effect. The 55 only difference in operation will be that after the operation of relays R, T and TT, as previously described, relay Q will remain energized, through a locking circuit traced from plus through make contact 2 of relay G, winding Q1 and make contact 11 of relay Q to ground.

Condition 3.—This case considers the condition 65 wherein the leakage resistance is low enough to hold in both the L and G relays, in which case the difference from the preceding examples will be that relay Q holds in simultaneously through the locking circuits described for the previous two cases. R does not energize in this case and T remains operated while TT drops after a delay due to the shunt across its coil through make contact 10 of relay T and back contact 11 of relay R.

Condition 4.—This case considers the condition where the leakage resistance is so high that neither the L or G relays will hold in at the end of the signal, in which case the clearing operations are as covered under "Normal operation."

CASE 2

Leakage effect on "G" relay side of transmitter

Let us assume for this condition that a transmitter is in operation on the line circuit with the leakage on the side of the transmitter nearest the G1 relay winding. On the first break impulse, relay L will release, as in previous examples, but G may operate through the leakage resistance on the line circuit, if of sufficient value through the winding G1, as the neutralizing winding G2 is cut off. With the operation of relay G, a circuit is closed from plus battery, through make contact 2 of relay G, winding Q1, back contacts 12 of relay Q, 9 of relay R, 14 of relay B, line 37, 6 of relay TT and make contact 7 of relay T to ground, causing energization of relay Q, which locks itself in through make contact 11 of relay Q. This will take place before relay B has time to operate as it did in the previous cases, it being of the slow operating type. When contact 8 of relay Q opens the operating circuit of relay B, its circuit is cut preventing operation at a later time. Relay Q switches the incoming line circuits through make contact 6 of relay W, back contact 8 of relay B, winding L1, back contact 3 of relay B and make contact 5 of relay Q, through resistor to plus battery. It will be noted that for this case, the switching of the line circuit has placed both sides of the line in multiple to plus battery, whereas in the previous case, the two sides of the line were connected between the plus main battery and the minus auxiliary battery. After the energization of relay Q, relay R will energize through the circuit traced from plus battery, through make contact 14 of relay Q, winding R2, through back contact 2 of relay L to ground. Operation of R causes TT to energize through make contacts 13 of relay Q, 10 of relay R, line 22, and 10 of relay T. The remainder of the operation will be as coerced under the transmitter operation for the leakage conditions previously described, except that in this case the signal retransmission depends on the operation of relay L, relay G holds on the line leakage.

SHUNTED TRANSMITTER

Should a transmitter that is shunted directly, or is in a shunted loop be in operation, the first break impulse of the transmitter will have no effect on the relays, due to the shunt. On the first ground impulse, relay winding G2 is shunted out, therefore the G relay is energized by the current through its winding G1 and the ground at the transmitter. Relay winding L1 also is shunted out by the same ground but L may or may not drop out, depending on the speed relationship between it and the operating time of relay G. In any case, however, relay L will immediately re-energize through the circuit traced from plus through make contact 2 of relay G, line 38, make contact 12 of relay T, line 35, back contacts 26 of relay Q and 15 of relay B and winding L2 to ground. Relays Q and X energize through circuits previously traced for the first leakage case, that is where the leakage affects the L relay except X picks up through contact 17 of relay Q instead of 16 of relay B. Otherwise the remainder of the operation is as covered under "Normal operation," to the point where relays Q, Y and Z release on the long break impulse of the transmitter. In this case, however, due to the shunt across the box or portion of the line, the line circuit is immediately restored to its normal con-

dition, with the release of Q, thereby causing re-energization of relay L through the normal line supervising circuit previously traced. From this point on the operation of the relays are as covered under "Normal operation," from the point where Q releases causing energization of L.

OPERATION WITH LINE CIRCUIT IN TROUBLE CONDITION

OPEN CIRCUIT CONDITIONING OPERATION

Should a break occur in the line circuit the L relay will release due to the open condition in the circuit of its winding L1. This in turn causes operation of relay B through the circuit traced from plus through winding BR, through back contacts 8 of relay Q, 12 of relay B and 2 of relay L to ground. Relay B locks in through the circuit traced from plus battery, through winding BR, back contact 8 of relay Q and make contact 9 of relay B to ground. Simultaneously relay R operates through the circuit traced from plus battery through back contact 1 of relay G, back contact 15 of relay Q, winding R2 and back contact 2 of relay L to ground. Relay TT is energized through make contacts 5 of relay B, 10 of relay R, line 22, 10 of relay T, winding of relay TT and resistor to ground. At the same time a shunt is applied to relay T by contact 5 of relay R, which causes its release after a short delay. With the release of relay T, relay TT drops out, due to the shunt across its winding by back contact 11 of relay T, line 33, make contact 12 of relay R, line 34, and back contact 3 of relay V. The release of T energizes X through the circuit traced from plus battery through make contact 7 of relay R, line 24, back contacts 4 of relay Y, 7 of relay Z, 9 of relay T, and winding X1 to ground. This completes the relay operations to condition the line circuit for transmitter operation.

TRANSMITTER OPERATION

Should a transmitter start operation on either side of the open condition, its ground impulses will control the operation of either the L or G relays. In the case of the L relay, the coding impulses will be transmitted from the transmitter ground, through the line, make contact 4 of relay B, winding L1, make contact 7 of relay B, and resistor to minus auxiliary battery.

On the other side of the open the line coding circuit extends from the transmitter ground through winding G1 to plus main battery.

On the first ground impulse of the transmitter, either relay L or G operates, causing release of relay R by breaking the circuit through its winding R2. The remainder of the code operation is the same as covered under "Normal operation," except that only one of the line relays will be coding, causing operation of relay R. Relay Q is not energized. At the time of the long break at the end of the round of signals, either relay L or G will release, causing operation of relay R. This in turn causes release of relays T, TT, Y and Z as previously covered. As the code springs pass over the normal segment, no change takes place in the line relays due to the fact that the line circuit is open. The remainder of the rounds of the multi-round transmitter are transmitted in the above described manner and the clearing operations will be the same as on the long break at the end of each round.

GROUNDED CIRCUIT OPERATION

GROUND CONDITIONING OPERATION

Should a line circuit become grounded, that ground will shunt the G2 and L1 relay windings, causing operation of relay G, by means of winding G1. The circuit for operation of G may be traced from plus battery through winding G1, through the line circuit to the ground. Relay Q then energizes through the circuit traced from plus battery, through make contact 2 of relay G, winding Q1, back contacts 12 of relay Q, 9 of relay R, 14 of relay B, line 37, 6 of relay TT and make contact 7 of relay T to ground.

Relay L is temporarily shunted out by the ground on the line circuit but reenergized upon the operation of relay G through its local winding from plus through make contacts 2 of relay G, line 38, and 12 of relay T, line 35, back contacts 16 of relay Q and 15 of relay B, and winding L2 to ground. This circuit is opened, as contact 16 of relay Q opens, but at the same time the plus battery is applied to the return side of the line through make contact 5 of relay Q, back contact 3 of relay B, winding L1, back contact 8 of relay B, make contact 6 of relay Q and line 4, enabling L to remain energized through the ground on the line.

The operation of relay Q causes operation of relay X energizing winding X2 through a circuit traced from plus through break contacts 8 of relay R, line 25, 9 of relay Z, 8 of relay Y, line 26, contact 17 of relay Q, line 27, back contact 8 of relay U and winding X2 to ground.

TRANSMITTER OPERATION

On the first break impulse of a code signal, either L or G will release depending on which side of the ground the transmitter is operated. This causes energization of relays R and TT and release of relay T in a similar manner to that described for other signals. On the first ground impulse of the first digit of the code, the de-energized line relay L or G reenergizes, causing release of relay R and energization of relay T. The remainder of the code is transmitted in a similar manner to that previously described.

During the long break at the completion of the code, relays L or G and R, T, TT, Y and Z function as covered under "Normal operation." When the line circuit is closed at the normal segment of the code wheel, relay L or G reenergizes, releasing relay R. When the transmitter comes to a stop, this in turn causes energization of relay TT, T and subsequent release of TT, through circuits previously traced for the other cases.

OPEN GROUND TROUBLE CONDITION

CIRCUIT CONDITION OPERATIONS

This trouble condition consists of an open condition on the outgoing side of the line circuit with a ground on the return side of the open condition. The outgoing side of the line circuit is that which is connected to battery at the central station.

Case 1

Open first.—In this case we will consider the condition where the break shortly precedes the ground. On the break in the line circuit, relay L will release, causing operation of relay B, and energization of relays R, TT, and X in a similar manner to that described for the open circuit

trouble condition. Relays T and TT may then release in a like manner, if sufficient time elapses before the ground comes on the line. When this happens, on the return side for this example, the L relay will reenergize through this ground through make contact 4 of relay B, winding L1, make contact 7 of relay B, resistor to the minus auxiliary battery. This causes release of R due to the break in the circuit of winding R2, at back contact 2 of relay L. Release of R energizes relay TT if it has previously released, through the circuit traced from plus through back contact 13 of relay R, line #3, back contact 11 of relay T, winding of relay TT and resistor to ground. Closing of contact 2 of relay TT energizes relay T through circuits previously discussed, this in turn causing release of relay TT. Relay X stays energized from plus through back contact 8 of relay R, line 25, contacts 6 of relay X, line 26, 16 of relay B, line 27, back contact 8 of relay U, and winding X2 to ground.

TRANSMITTER OPERATION

Assuming a transmitter in operation on the grounded side of the line, on the first break impulse relay L releases, in turn energizing R and TT, deenergizing T in a similar manner to that described for the open circuit trouble condition. On the first ground impulse of the code, relay L will reenergize, causing release of relays R and TT, deenergizing T in a similar manner to that previously described. The remainder of the code will be transmitted as covered under "Open circuit operation," except when the transmitter arrives at the normal segment at the end of the transmission of the code, relay L reenergizes, through the ground trouble on the line circuit, causing release of relay R with subsequent re-energization of relays TT and T through circuits previously traced. Energization of relay T causes release of TT by reestablishing the shunt by make contact 10 of relay T and back contact 11 of relay R across its winding.

Assuming a transmitter to be in operation on the open side of the line, no change will take place on the transmitter operation until the first ground impulse of the code is transmitted, at which time relay G picks up through its winding G1, this in turn causing energization of relay Q through its winding Q1 through circuits previously traced. The operation of contact 8 of relay Q breaks the holding circuit for the B relay, causing its release, thereby switching the line relay winding L1 from the auxiliary battery to the main battery. On the first break impulse relay G releases, causing energization of relay R through its winding R1 and make contact 2 of relay Q. Relays TT and U energize in succession through circuits previously traced. The remainder of the operation is as covered under ground circuit operation except at the time the transmitter contacts close on the normal segment. As in this case the line is open, the contact closure on the normal segment produces no further effect on the line relay Q, R and X remain energized.

Case 2

In this case we will assume that a ground occurs slightly before the break, in which case the switching operation takes place to condition the line for transmitter operation as covered under grounded operation.

On the ground the G2 relay winding is shunted out as previously described, thus causing operation of relay G, through its winding G1 and the

Special attention signals

Signals which require special attention by the operator will record on the register with the first digit as a "1." The code wheel of the transmitter, however, will be cut with two teeth as has been previously explained; the effect of the first tooth of the code is eliminated by the relays.

On the first break or ground impulse, depending on the line circuit condition or during switching arrangements to condition the line circuit for proper operation the X relay is energized as previously covered in the description. As previously explained, relay R energizing on the break impulse following the first ground impulse of the first digit causes operation of relay U. To review, this circuit is traced from plus through make contact 1 of relay TT, line 29, make contact 4 of relay R, line 30, back contact 1 of relay Z, make contact 1 of relay X, winding of relay U and make contact 4 of relay T to ground. Relay U locks in through its make contact 1 of relay U. Up to this time any coding circuit through the register has been open at make contacts 12 of relay U, 1 of relay Y or 2 of relay Z. On the second ground impulse of the code when relay R releases, a circuit is completed to the register which may be traced from plus battery, through make contact 1 of relay TT, line 29, back contact 3 of relay R, line 31, make contact 2 of relay U, through the resistor and register coils to ground. At the same time relay X releases as its holding circuit through winding X1 is broken at make contact 7 of relay R and the holding circuit through winding X2 is broken at back contact 8 of relay U.

On the next break impulse of the code, relay Y is energized through the circuit traced from plus through make contacts 7 of relay R, line 24, 6 of relay U, back contacts 3 of relay X and 8 of relay Z, winding Y1 and make contact 4 of relay TT to ground. Relay Y locks in through its make contact 5 of relay Y, at this time.

Due to the longer break impulse at this time (two teeth being removed on the code wheel after the first digit), relay T has time to release due to the shunt effect of contact 5 of relay R across its winding T. This in turn causes release of relay U due to the opening of contact 4 of relay T in its circuit. At the same time, an impulse is initiated to a special attention relay through the circuit traced from ground through back contact 5 of relay U, make contact 3 of relay Y and relay 50. On the subsequent release of relay R on the next ground impulse, an impulse for the second digit is transmitted through the register through the circuit previously traced, except this time through make contact 1 of relay Y instead of 2 of relay U. At the same time the relay Y locking circuit is established through winding Y2, from plus, through the back contact 8 of relay R, line 25, make contacts 1 of relay TT, 9 of relay Y and winding Y2 to ground. Relay X cannot be reenergized at this time through winding X2 due to open at contacts 6 of relay X, 8 of relay Y and make contact 7 of relay U. At this time relay V is energized from plus through back contacts 8 of relay R and 3 of relay U, contact 2 of relay Y and winding V1 to ground. Relay V locks in from plus through contacts 7 of relay TT and 1 of relay V and winding V2 to ground.

This relay operates its contact 2 of relay V thereby introducing resistance into the shunt circuit of relay TT through back contact 11 of relay T, line 33, and make contact 12 of relay R, reducing its time delay. This is preparatory to the re-

ground on the line circuit to the main battery, this in turn causing operation of the relays Q and X. When the open condition occurs, for this case on the outgoing side of the line, relay G will release, causing energization of relay R, through the circuit traced from plus through back contact 1 of relay G, winding R1, and make contact 2 of relay Q to ground. Relays R and TT function in the same manner as covered in other cases for the first operation of relay R.

Assuming a transmitter to be in operation on the grounded side of the line, the first break impulse will cause release of relay L, which in turn causes release of relay Q by breaking its holding circuit through winding Q2 at the make contact L. Relay B will energize through the circuit traced from plus battery through winding BR, through back contact 8 of relay Q, back contact 12 of relay B, and back contact 2 of relay L to ground. B locking in through the operation of its make contacts 11 of relay B and 9 of relay B. On the first ground impulse, relay L reenergizes, causing release of relay R. The remainder of the operation taking place as covered under Case 1, with a transmitter in operation on the grounded side of the line.

Assuming a transmitter in operation on the open side then the first ground impulse from a transmitter will cause energization of relay G by means of winding G1 to plus battery. This in return causes release of relay R by the break at back contact 1 of relay G. Relays TT and T energize through circuits previously traced. The remainder of the operation will be understood from the above.

GROUNDED OPEN LINE TROUBLE*Case 1*

In this case we will assume that the open condition occurs before the ground in point of time. At the time of the open condition the relays switch exactly as covered under "Open circuit operation" up to the point where relay TT releases and X is energized. At this time we will assume that the ground occurs, this will cause energization of relay G through its winding G1 to plus main battery. The subsequent functions of the relays R, TT, T and X are the same as for Case 1 under the open ground condition.

Transmitter operation on either side of the line is similar to that covered under "Open ground operation."

Case 2

For this ground open condition we will assume that the ground occurs shortly before the open. In this case relays G, Q and X are energized as covered under "Grounded operation." On the open the relay operation is the same as for open grounds, Case 2, except that relay L releases in place of relay G. The operation of the transmitter on either side of this trouble condition is otherwise similar to that covered under "Open ground operation."

ROUTING OF SIGNALS

In addition to the relays used for line and register control, three relays, namely X, Y and Z are utilized for the purpose of routing the various types of signals. These signals are of the four classes listed below:

1. Special attention
2. Police
3. Fire alarm
4. Routine

lease of TT during the long break at the end of the code. Previously this shunt acted directly across the coil of TT resulting in longer delay, in order to prevent TT from dropping out during the fairly long break after the first digit caused by the removal of two teeth on the code wheel. Without this arrangement a longer break than now used would be necessary at the end of the code where a minimum of four teeth is removed, resulting in reduced code capacity. It is to be noted that only one tooth is removed between succeeding digits, so that the reduced time delay of TT will still be sufficient to keep it energized during the longer break impulses between the following digits.

On the subsequent energization of R, on the first break impulse of the second digit, no further change takes place in the routing relays as the circuit of the winding X_1 is open at contacts 7 of relay X and back contact 4 of relay Y, and the circuit to winding Z_1 is open at make contact 5 of relay X. Relay Y stays locked in through the previous locking circuit traced from plus through make contact 1 of relay R, line 24, make contact 5 of relay Y, break contact 8 of relay Z, winding Y_1 and make contact 4 of relay TT to ground. During ground impulses when make contact 1 of relay R is open and back contact 8 of relay R is closed, relay Y is held energized from plus through back contact 8 of relay R, line 25, contacts 7 of relay TT and 9 of relay Y and winding Y_2 to ground. The remainder of the digits of the code are transmitted into the register through make contact 1 of relay Y instead of 2 of relay U and cause no further change in the routing relays.

At the completion of the signal relay Y is de-energized due to the opening of contact 4 of relay TT, causing operation of relay X from plus through make contact 1 of relay R, line 24, back contacts 4 of relay Y, 1 of relay Z, 4 of relay T and winding X_1 to ground. Relay V releases due to the opening of contact 1 of relay TT. An attention relay whose operation will be described at a later point remains locked in. This relay initiates a buzzer and lamp signal to indicate that the supervisor's attention is required for the particular signal transmitted.

Police signals

A signal from a transmitter which requires the attention of the police department will have the first digit of the code record as a "2," the code wheel of course being cut as previously described, with an extra tooth in the first digit. The operation of the routing relays will be the same as covered under "Special attention signals" up to the point where relay Y is energized. As the next ground impulse occurs after the regular break space, relay T does not have sufficient time to release before relay R release, relay R sends a second impulse to the register for the first digit of the code. At the same time relay X is energized through the circuit traced as follows: From plus battery, through back contact 8 of relay R, line 25, back contact 9 of relay Z, make contact 7 of relay Y, make contact 7 of relay U, and winding X_2 to ground. On the subsequent break impulse, which will be of longer duration, relay Z will energize through the circuit traced from plus battery through make contacts 7 of relay R, line 24, 5 of relay Y, 5 of relay X, and operating winding Z_1 to ground. Relay Z locks in through the circuit traced from plus battery through make contact 1 of relay TT, make contact 11 of relay Z and winding Z_2 to ground. Relay T releases after a

short delay deenergizing relay U. On the first ground impulse of the second digit relay V is energized. These operations are the same as explained in the previous case.

No further change takes place in the condition of the routing relays due to open circuits in the circuits of the various operating windings. The remaining digits of the code are transmitted to the register through circuits previously traced and in addition routed to terminal 13 where they control retransmission to police headquarters repeater relay P. H. Q. This circuit may be traced from ground through back contact 6 of relay R, line 40, back contact 4 of relay U, make contact 5 of relay Z, make contacts 8 of relay X and 19 of relay Y to the police headquarters. The circuit controls the retransmission over a headquarters circuit. The circuit to the "Special attention" terminal 12 is also closed as described in the previous case.

Fire alarm signals

Signals which require the attention of the fire department will record the first digit of 3 on the register, which, of course, necessitates cutting the code wheel with four teeth to cover the elimination of the first impulse as previously described. The operation of all routing relays is the same as covered under Police signals up to the time of the second break impulse of the code when the Z relay is energized. This impulse is of ordinary length, thereby not allowing sufficient time for relay T to release when during the next ground impulse relay R releases. Relay X de-energizes, as its holding circuit is open at back contact 8 of relay U and back contacts 9 of relay Z or 6 of relay Y. At this time a third impulse will be transmitted to the register through circuits previously traced. On the following break impulse relay R operates again and relay Y releases, as its holding circuit is open at back contact 8 of relay Z and make contact 4 of relay X. Due to the longer time between digits, relay T has time to release, in turn causing release of relay U as previously described. On the first ground impulse of the second digit, relay V is energized this time through contact 4 of relay Z instead of 2 of relay Y.

The remainder of the digits of the code will be transmitted to fire headquarters through the circuit traced as follows: From ground, through back contact 8 of relay R, line 40, back contact 4 of relay U, make contact 5 of relay Z and back contact 9 of relay X to the fire headquarters repeater relay F. H. Q. At the same time a special attention signal is initiated through the circuit traced from ground through back contact 5 of relay U, make contact 6 of relay Z and back contact 2 of relay X to the special attention relay 50. Contact 2 of relay Z being closed, permits the remaining digit to be retransmitted to the register.

Night watch and routine signals

These signals have a "4" or higher number as the first digit. In this case all selector relay operations take place as covered under "Fire alarm signals" up to the point where relay Y releases. Due to the fact that the particular break impulse is of normal short duration, it is not sufficient to allow for release of relay T. On the next ground impulse relay X is again energized through the circuit traced from plus through back contact 8 of relay R, line 25, make contact 10 of relay Z, back contact 6 of relay Y, make contact 7 of relay U, through winding X_2 to ground. On the

subsequent break impulse at the completion of this digit relay X remains energized through winding X¹ and contact 7 of relay X. For additional ground and impulses for digits higher than 4, no further change takes place with respect to relays X, Y and Z. On the long break following the first digit, relay T releases causing release of relay U in a manner similar to that previously described. On these signals it will be noted that all circuits are open to the police and fire headquarters terminals as well as the special attention terminal.

TROUBLE INDICATIONS OF OPEN LINE CIRCUIT

A trouble indication will be initiated through the circuit traced from ground through back contact 1 of relay Q, make contact 2 of relay B, in multiple with back contact 2 of relay T, through resistor and the trouble light through switch blades FS/1 and SS/1 in the normal position to the trouble relay. A parallel circuit extends from the above mentioned relay contacts through switch blades SS/2 and FS/2 and the trouble relay. To silence the buzzer associated with this signal, the switch SS shall be thrown, thereby causing release of the trouble relay but leaving the lamp lit by a direct connection to plus battery. Upon restoration of the trouble, the lamp is extinguished due to the open condition at back contact 2 of relay T and make contact 2 of relay B. At the same time the buzzer will again sound, this time a circuit being traced from ground through back contacts 1 of relay Q, 1 of relay B, switch blade SS/2 in the right hand position, switch blade FS/2 in the normal position, resistor through the winding of the trouble relay to plus battery. To silence the buzzer the switch SS shall be thrown back to its normal position.

TROUBLE INDICATION—LINE CIRCUIT GROUNDED

The trouble indication for this condition is initiated through the circuit traced from ground through make contact 2 of relay Q, through resistor, the trouble light and switch blades FS/1 and SS/1, also through switch blades SS/2 and FS/2 and resistor r₅, to the trouble terminal 10 to operate the trouble relay as previously described. Throwing the switch SS, connects the light directly to plus battery and causes release of the trouble relay to silence the buzzer. On restoration of the line circuit through the normal condition, relay Q releases, closing a circuit from ground through back contacts 1 of relay Q, 1 of relay B, switch blade SS/2 which will now be in the right hand position, switch blade FS/2 and resistor to again energize the trouble relay. To silence the buzzer the switch SS shall be thrown to its normal position.

For combination troubles of grounds and opens, similar circuits can be traced.

POWER SUPERVISION

Line relay panel fuse

In the case where a trouble, particularly in the local circuiting, causes blowing of the panel fuse, all relays release. A circuit is then closed from ground through back contact 2 of relay T, line 41, resistor, the lamp through switch blades FS/1 and SS/1, also through blades SS/2 and FS/2 and resistor r₆, through the trouble relay to plus battery supply, which is not taken through the fuse, it being located on a separate panel unit. To silence the buzzer, the switch FS shall

be thrown. This transfers the trouble light directly to plus battery on the main fuse and silences the buzzer. Upon restoration of the power by replacing the panel fuse after the trouble is cleared, the lamp is extinguished and a buzzer signal initiated through the circuit traced from ground through make contact 6 of relay T, switch blade FS/2 in the right hand position, resistor, through the trouble relay winding to plus battery. To silence the buzzer the switch FS shall be thrown to its normal position.

It will be noticed that it is not possible to silence the buzzer signal in any other way but by the switch operations indicated, thus giving the operator an indication of the nature of the trouble.

The preferred embodiment of the various parts of the above described system have been shown, but it should be understood that further modifications will occur to those skilled in the art, and therefore it is desired that this invention shall be limited only to the extent required by the prior art and the appended claims.

What is claimed is:

1. In a signaling system, a plurality of code transmitters for transmitting signals of a plurality of types, each transmitter comprising a prefix digit for identifying the type of signal and other digits for identifying the transmitter, first timing means, selecting means responsive to the prefix digit under the control of said first timing means actuated at the end of the prefix digit, second timing means for restoring the selecting means to normal at the end of a signal and means responsive to the first impulse of the second digit for reducing the timing of the second timing means.

2. In a signaling system, a plurality of code transmitters for transmitting signals of a plurality of types, a plurality of receivers for said types of signals, each transmitter comprising a prefix digit for identifying the type of signal and other digits for identifying the transmitter, first timing means, selecting means responsive to certain prefix digits for selecting a receiver, said selecting means being under the control of said first timing means actuated at the end of the prefix digit, second timing means for restoring the selecting means to normal at the end of a signal and means responsive to the first impulse of the second digit for reducing the timing of the second timing means.

3. In a signaling system, a code transmitter for transmitting signals comprising a prefix digit for identifying the signal and other digits for identifying the transmitter, a plurality of receivers, routing means responsive to the prefix digit for switching the signals to the proper receiver, timing means for restoring the routing means to normal at the end of a signal, another timing means responsive to the end of the prefix digit for switching the remainder of the code, switching means responsive to the first impulse of a second digit for reducing the timing of the first timing means and contacts operated by the routing means for operating the switching means.

4. In a signaling system, a code transmitter for transmitting signals comprising a prefix digit for identifying the signal and other digits for identifying the transmitter, a repeating relay for repeating the code signal, a plurality of receivers, routing means responsive to the prefix digit for switching the signals to the proper receiver, timing means for restoring the routing means to normal at the end of a signal, another timing

means responsive to the end of the prefix digit for switching the remainder of the code, switching means responsive to the first impulse of a second digit for reducing the timing of the first timing means and contacts operated by the routing means for operating the switching means.

5. In a signaling system, a code transmitter for transmitting signals comprising a prefix digit for identifying the signal followed by a plurality of digits identifying the transmitter, a plurality of receivers, routing means responsive to the prefix digit for routing the signals to the proper receiver, a timing relay responsive to the end of a signal for restoring the routing means to normal, another timing relay responsive to the break after the prefix digit for timing the prefix, a switching relay responsive to the first impulse of the second digit for reducing the timing of the first timing relay and contacts operated by

the routing means for operating the switching relay.

6. In a signaling system, a code transmitter for transmitting signals comprising a prefix digit for identifying the signal followed by a plurality of digits identifying the transmitter, a repeating relay for repeating the digits, a plurality of receivers, routing means responsive to the prefix digit for routing the signals to the proper receiver, a timing relay responsive to the end of a signal for restoring the routing means to normal, another timing relay responsive to the break after the prefix digit for timing the prefix, a switching relay responsive to the first impulse of the second digit for reducing the timing of the first timing relay and contacts operated by the routing means for operating the switching relay.

MANFRED W. MUEHTER.
